UNITED STATES PATENT OFFICE

165,178

MOBILE FLOWER SHOP

Ray C. Ludwig, Englewood, Colo.

Application June 17, 1949, Serial No. 3,378

Term of patent 14 years

(Cl. D14—3)

To all whom it may concern:

Be it known that I, Ray C. Ludwig, a citizen of the United States, residing at Englewood, in the county of Araphoe and State of Colorado, have invented a new, original, and ornamental Design for Mobile Flower Shop, of which the following is a specification, reference being had to the accompanying drawing, forming a part thereof.

The characteristic features of my design reside in the portions shown by means of full lines in the drawing and especially the interior portions shown by Figs. 2, 3, 4, 5 and 6.

I claim:

The ornamental design for a mobile flower shop, as shown and described.

RAY C. LUDWIG.
